DESIGN FOR A MILK BOTTLE

Bo Adlerbert, Scotch Plains, N. J.

Application January 25, 1945, Serial No. 117,605

Term of patent 14 years

(Cl. D58—6)

To all whom it may concern:

Be it known that I, Bo Adlerbert, a citizen of the United States, residing at Scotch Plains, in the county of Union and State of New Jersey, have invented a new, original, and ornamental Design for Milk Bottles, of which the following is a specification, reference being had to the accompanying drawing, forming part thereof.

The figure is a perspective view of a milk bottle, showing my new design.

I claim:

The ornamental design for a milk bottle, as shown.

BO ADLERBERT.
